CLAIM

The ornamental design for a handle for container, as shown and described.

DESCRIPTION

FIG. 1 is a perspective view of a handle designed according to the present invention;

FIG. 2 is a front view in elevation of the same handle;

FIG. 3 is a rear view in elevation of the same handle;

FIG. 4 is a plan view of the same handle;

FIG. 5 is a side elevation of the handle; and,

FIG. 6 is a bottom view of the handle.

The left-side view of the handle is a mirror image of the right side view.

The broken line disclosure in FIGS. 2, 4 and 6 is for illustrative purposes only and forms no part of the claimed design.
